UNITED STATES PATENT OFFICE.

FREDERICK W. THACKERAY AND JOHN ROY MILLIKEN, OF LOS ANGELES,
CALIFORNIA.

DISAPPEARING SHOE STAND.

Application filed November 9, 1923. Serial No. 673,718.

To all whom it may concern:

- Be it known that we, FREDERICK W. THACKERAY and JOHN ROY MILLIKEN, citizens of the United States, residing at Los Angeles, in the county of Los Angeles and State of California, have invented new and useful Improvements in Disappearing Shoe Stands, of which the following is a specification.
- 10 This invention relates to disappearing furniture and more particularly to disappearing wall furniture.
- An object of the invention is to provide a disappearing footrest or shoe-stand.
- 15 Another object is to provide, in combination with a wall, a disappearing foot-rest and panel whereby the foot-rest can be quickly and effectively concealed in a recess in the wall and of which recess the panel
- 20 forms the front closure.

A broad object of the invention is to provide a disappearing, wall shoe-polishing stand.

Another object is to provide a self-contained shoe-shining cabinet for installation between the studding of a wall or portion of a building.

We accomplish these objects by a structure and mechanism, of which one practical embodiment is herein disclosed by the following description of the accompanying drawings and the novel features thereof set forth in the appended claims.

Referring to the drawing:

35 Fig. 1 is a perspective view, showing the cabinet installed in a wall and showing the stand as it appears when in use.

Fig. 2 is a perspective view taken from the rear or opposite side of the wall from that shown in Fig. 1 and showing the parts as they appear when the cabinet is closed, parts being broken and shown in section.

Fig. 3 is a sectional elevation, taken on line 3—3 of Fig. 2.

45 Fig. 4 is a section on the same plane as Fig. 2, but showing the cabinet in open position.

Referring by numerals to the accompanying drawings, 10 represents a wall construction, such as lath and plaster, the studding being shown at 11 resting on sills 12 and

flooring 13, such studding being amply spaced to allow the installation of a shoe-shining cabinet constituting the invention generally as designated at 14.

The cabinet consists of side members 16 to which are fastened top and bottom plates 17 and 18 and between the top and bottom is a shelf 19, the entire back consisting of a single plate 20. The front of the cabinet 60 has a door having upper and lower sections 22 and 23, the upper section 22 being hinged at 24 to the lower section 23, while the lower section is hinged at 25 to a panel 26. The upper section 22 is held in closed position by a friction latch 27 and is also provided with a handle 28 and clip 29 for holding a whisk-broom or brush. The inner side of the door section 23 is provided with frames or brackets 30 for holding brushes, as shown in Figs. 70 1 and 2.

In order to produce a finished appearance, the panelling 31 is fastened to the members 16 and 17, while the panel 26 is fastened to the member 18.

In order to hold the cabinet in place, the panelling 31 and the sides 16 are nailed to the studding 11.

The interior elements of the cabinet include a folding shoe-stand, generally designated as 32, which is operated by the opening and closing of the door 23. The stand consists of a foot-rest 33 having portions 34 and 35 for supporting the sole and heel of a shoe S and also to sustain any weight or pressure applied thereon by the wearer of the same. (See Fig. 1.)

The sole portion is supported when in use, as shown in Figs. 1 and 4, by a standard 36 preferably made of a single piece of wire 90 extending through an opening O in the foot-rest, as shown at 37, and for strengthening purposes the ends 38 are twisted as at 39 and then bent outwardly as shown at 40. These ends slide in a guide 41 fastened to the door section 23, said guide having flanges 42 to hold the ends 40 in place. The underside 43 of the guide 41 is bent up at 44 to form a stop 45 to receive the ends 40 of the standard 36 which is held in a position to engage the stop 45 by a spring 46, one end of which is fastened to a foot-rest.

33 as designated at 47, while the other end engages the standard 36 below the twisted portion 39, as designated at 48.

In order to support the door 23 when in open position, a U-shaped link, preferably formed of one piece of wire, is utilized, having arms 50 being bent outwardly in opposite directions and hinged at 51 to the shelf 19, while the intermediate portion 52 extends to the opening O of the foot-rest 33. The heel portion 35 of the foot-rest 33 is supported by a U-shaped link 53 having arms 54 pivoted on a shaft 55 mounted in brackets 56 fastened to the door section 23, while the intermediate portion 57 extends through an opening 58 adjacent to the heel portion 35.

In order to cause the foot-rest to assume a predetermined angle, when the door is opened and effect the movements of the links 50 and 53 in conjunction with the standard 36, a U-shaped link 59 having arms 60 is pivoted to the shaft 55, while the cross-piece 61 extends through the opening O in the foot-rest 33. The door 23 and the shoe stand 32 are held in a closed position in addition to the latch 27 on the door 22 by a friction clip 62 engaging the heel portion 35 of the foot-rest 33.

In order to use the shoe-stand, it is only necessary to open the door section 22 and then pull it forward, which will also open door 23, and in so doing the parts comprising the shoe-stand will automatically move from the closed position shown in Figs. 2 and 3 to the open position in the Figs. 1 and 4; this action being assisted by tension of the spring 46.

When it is desired to close the doors and fold the shoe-stand into the closed position, it is only necessary to lift the portion 40 of the stand 36 out of the latch 45.

It will be seen that the shoe-shining cabinet may be readily installed in the wall of a building during the course of construction, or put into the walls of a building already constructed, with very little alteration. The cabinet provides a convenient storage place for polish and other articles, while the shoe-shining stand provides a very convenient and substantial shoe-rest, thus avoiding the inconvenience and possible defacing of household furniture when used for the purpose of shining shoes.

Further embodiments, modifications and variations may be resorted to within the spirit of the invention.

What is claimed is:

1. A disappearing shoe stand comprising in combination a wall cabinet, a front panel pivoted adjacent the base thereof, a foot rest, arms attached to the inside of the cabinet and engaging the toe portion of the foot rest, links engaging the upper end of the pivoted panel and connected to the foot rest,

a standard between the foot rest and the pivoted panel, and means whereby the foot rest, arms, links and standard may be folded within the cabinet when the pivoted panel is closed.

2. A cabinet having a hinged door, and a foldable shoe stand having a foot-rest pivotally connected to said cabinet and door, a standard connected to said foot-rest and slidably attached to said door, the latter having a stop engaged by the standard when said standard is moved from a folded to an open position by opening of the door, said standard supporting said foot-rest and being held in engagement with said stop by a spring connected to said standard and to the foot-rest.

3. A disappearing shoe stand comprising in combination a wall cabinet, a front panel pivoted adjacent the lower end of the cabinet, a shoe rest, arms connecting the toe portion of the shoe rest to an interior portion of the cabinet, links connected to the heel and toe portions of the foot rest and engaging the panel, a standard connected to the toe portion of the foot rest and engaging the panel, the said panel when occupying an inclined position holding the foot rest in inclined position, and means to allow folding of the foot rest, arms, links and standard in the interior of the cabinet when the panel is closed.

4. In a disappearing shoe stand, a cabinet having a shelf, a door section hinged at its lower end to said cabinet to swing outwardly and inwardly below the shelf, a foot rest, a standard pivotally connected to the toe portion of the foot rest and extending downwardly, a slide upon the inner face of the door section, a connection between the lower end of the standard and the slide, a stop at the upper end of the slide to be engaged by the standard, arms connected to the toe portion of the foot rest and connected to the shelf, and arms connecting the heel portion of the foot rest to the upper end of the door section.

5. In a disappearing shoe stand, a cabinet having a shelf, a door section hinged at its lower end to said cabinet to swing outwardly and inwardly below the shelf, a foot rest, a standard pivotally connected to the toe portion of the foot rest and extending downwardly, a slide upon the inner face of the door section, a connection between the lower end of the standard and the slide, a stop at the upper end of the slide to be engaged by the standard, arms connected to the toe portion of the foot rest and connected to the shelf, arms connecting the heel portion of the foot rest to the upper end of the door section, and a retractile spring connecting the lower end of the standard to the heel portion of the foot rest.

6. In a disappearing shoe stand, a cabinet

having a shelf, a door section hinged at its lower end to said cabinet to swing outwardly and inwardly below the shelf, a foot rest, a standard pivotally connected to the toe portion of the foot rest and extending downwardly, a slide upon the inner face of the door section, a connection between the lower end of the standard and the slide, a stop at the upper end of the slide to be engaged by 10 the standard, arms connected to the toe por-

tion of the foot rest and connected to the shelf, arms connecting the heel portion of the foot rest to the upper end of the door section, and arms connecting the upper end of the door section to the toe portion of the 15 foot rest.

In testimony whereof we have signed our names to this specification.

F. W. THACKERAY.
JOHN ROY MILLIKEN.
